UNITED STATES PATENT OFFICE.

ERNEST MAURICE BALLOT, OF PARIS, FRANCE.

DISTRIBUTING APPARATUS FOR ENGINES OR THE LIKE.

1,089,811.

Specification of Letters Patent. Patented Mar. 10, 1914.

Application filed January 17, 1911. Serial No. 603,096.

To all whom it may concern:

Be it known that I, ERNEST MAURICE BALLOT, a citizen of the Republic of France, residing at Paris, in France, have invented 5 new and useful Improvements in or Relating to Distributing Apparatus for Engines or the like, of which the following is a specification.

This invention relates to improvements in 10 the distributing mechanism for engines, pumps or the like, and consists in dispensing with the control of the distributor by a lever and replacing it with a direct control by a special cam. Also according to this invention multiple orifices are used for admission and exhaust.

In the accompanying drawing given merely by way of example, Figure 1 is a vertical section through the axis of rotation 20 of the controlling or driving cam of a distributing element. Fig. 2 is a vertical section in a plane at a right angle to that of Fig. 1.

The cylinder 1 of the motor has a hemi- 25 spherical head 2 provided with a branch 3 for the admission of the explosive mixture, and another branch 4 for the exhaust of the products of combustion. In this construction the head 2 is moreover provided with 30 ports 5 and 6 in communication by means of suitable conduits, with the branches 3 and 4 respectively. The hemi-spherical cap 7 which constitutes a movable part of the distributor, is in its turn provided with ports 35 8 which can come alternately opposite the ports 5 and 6 of the head 2. The cap 7 is provided with an outside projection 9 which can move freely in a groove 10 made in the end 2 and forming a guide for said projection. Through the said projection passes a 40 rod 11 suitably secured to it by means of pins 12, and at its end the projection 9 is turned to cylindrical shape for receiving a roller 13 mounted loosely on it. The cylinder 45 end is surmounted by a box 14 closed by a cover 15, and two of the faces of the said casing are provided with bearings 16 intended to receive the journals of a spindle 17. The box 14 is intended to contain oil 50 for insuring lubrication of the distributing mechanism.

In the interior of the box 14, to two of its opposite faces, are secured two hooks 18 to which are attached the ends of helical springs 19 hooked at their other ends respectively to the two ends of the rod 11 on which they pull so that the cap 7 is held against the inner wall of the end 2. To the spindle 17 is secured a cam 20 which can be made in one piece with it. This cam which is not cylindrical, has a special shape of revolution; it is generated by the rotation about the geometrical axis of the spindle 17 of a "meridian" having the same center *o* as the cap 7 and the inner wall of the hemispherical end 2. The said cam 20 is provided with a groove 21 of constant depth for receiving the roller 13, and its shape in development is, of course, determined so as to transmit to the cap 7 the different motions required for the distribution, which depend therefore directly on the rotation of the cam 20, the spindle 17 of which is driven by the shaft of the engine by means of a suitable gear.

It will be readily understood that, owing to the shape of the cam 20, the roller 13 is always, in its movement of advance, at a constant distance from the center *o*, which is an essential point. Thus, the ports 8 in 80 said cap during its operation by said cam will alternately register with the ports 5 and 6 in the cylinder head, the edge of said cap being effected for covering and uncovering the lowermost ports 5 and 6 of the cylinder. Owing to the multiplicity of the exhaust and admission ports, the said movement of advance of the roller 13 can be, moreover, of the least possible amplitude. It will be seen, finally, that the arrangement 85 on the head of the cylinder of conduits for the mixture to be drawn in, largely contributes to cooling it, as well as to cooling the movable cap which receives the fresh mixture at several points of its surface.

Having now particularly described and ascertained the nature of my said invention and in what manner the same is to be performed, I declare that what I claim is:

A distributing mechanism of the character described for engines, pumps or the like, comprising in combination a cylinder pro-

vided with ports in its head and having a semi-spherical cap provided with inlet and exhaust openings registering with said ports of the cylinder head, a cam with its meridian concentrically arranged to said cap for controlling the oscillation of the same and provided with a groove adapted to be engaged by a projection of said cap carrying a

roller, and springs tending to return the cap into its normal position.

In testimony whereof I affix my signature in presence of two witnesses.

ERNEST MAURICE BALLOT.
